BUCKLE FOR SAFETY BELTS

Sol Wexler, Syosset, N.Y., assignor to C & W Manufacturing Corp., New York, N.Y., a corporation of New York

Filed Apr. 25, 1962, Ser. No. 190,056
2 Claims. (Cl. 24—230)

This invention relates generally to safety belts and more particularly to a buckle construction for safety belts.

A principal object of the present invention is to provide a buckle construction that is relatively free from the possibility of accidental or inertia-operated unlocking.

Another object of the invention is to provide a buckle construction wherein the release lever does not function to maintain the two buckle components in engagement.

Still another object of the invention is to provide a buckle construction wherein the cam members function to hold the two buckle components together.

A specific object of the invention is to provide a single spring construction for biasing the cam members to a position holding the buckle components in engagement.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a top plan view of a buckle construction embodying my invention shown disassembled.

FIG. 2 is a part elevational and part sectional view through the longitudinal center of the buckle construction in assembled condition.

FIG. 3 is a cross-sectional view taken on the line 3—3 of FIG. 2.

FIG. 4 is a view similar to FIG. 2 but with the release lever moved to release position and the buckle components partially disengaged.

FIG. 5 is a perspective view of the cam assembly.

FIG. 6 is a cross-sectional view taken on the line 5—5 of FIG. 4.

FIG. 7 is a perspective view of the biasing means for the cam assembly.

FIG. 8 is a bottom plan view of one of the buckle components forming part of the invention.

Referring in detail to the drawings, a buckle construction embodying my invention is shown in FIG. 2 and designated generally by the reference numeral 10. The buckle construction 10 comprises broadly a buckle component or coupling member 12 and a buckle component or coupling member 14 for fastening the ends 16 and 18 of a belt 20 to each other.

The buckle component 14 is a flat metal rectangular plate 22 formed along one long edge with an elongated closed slot 24 for receiving the looped end 18 of the belt 20. A pair of spaced openings 26, 26 is formed along the other long edge of the plate to receive parts of the buckle component 12.

With particular reference to FIGS. 2 and 3, the buckle component 12 comprises a frame including a flat rectangular metal base 28 and parallel upstanding side flanges 30, 30. The base 28 is provided with upwardly bulged portions 32, 32 adapted to fit in openings 26, 26 of buckle component 14. The positioning of the openings 26, 26 in the component 14 and the formed portions 32, 32 on component 12 may be reversed if desired. The surfaces 34, 34 of the bulging portions 32, 32 are slanted with respect to a normal to the base 28 at an angle of twenty to twenty-five degrees, if the members are to be left in their original condition established by the forming dies.

2

The openings 26, 26 in the buckle component 14 are beveled from both sides along the edges 36, 36 so that these surfaces will conform to the surfaces 34, 34 regardless of the orientation in which the component 14 is shoved into engagement with the component 12.

The flanges 30, 30 provide for the mounting of a cylindrical shaft 38, the hexagonal head 40 of the shaft at one end being received in the similarly-shaped opening in the adjacent flange 30 to assure nonrotative positioning of the shaft with respect to the frame of the buckle. The shaft is formed with an elongated closed slot 42.

A pair of camming levers 44, 44 is rotatably mounted on the shaft 38 at its ends, the shaft passing loosely through holes 45, 45 in the levers. The shape and dimensions of the camming levers are selected so that a small amount of clearance is provided for the belt buckle component 14 when it is inserted in the fully engaged positions shown in FIG. 2. The purpose of the camming levers 44, 44 is to maintain the bulging portions 32, 32 of component 12 in locking position in the openings 26, 26 in component 14.

It will be noted from FIG. 3, that the flanges 30, 30 of the frame, the camming levers 44, 44 and the bulging portions 32, 32 of component 12 are positioned in such a manner that the camming levers 44, 44 are as close as possible to the flanges 30, 30 and the bulging portions 32, 32 are as close as practical to the camming levers 44, 44, respectively.

The buckle component 12 includes a release lever designated generally at 48. The release lever consists of a compound curved metal rectangular plate 50 formed with inwardly extending flanges 52, 52 along its long edges, the flanges at one end terminating in inwardly extending perforated ears 54, 54 forming bearings for bushings 55 through which the ends of shaft 38 pass to the flanges 30, 30. The other end of the plate 50 is turned outwardly abruptly forming a handle 56 for manipulating the lever. The short edge 70 of the lever at the end bearing the ears 54, 54 presses against the adjacent long edges 40 of the camming levers 44, 44. Metal washers 60, 60 are mounted on the shaft 38 between the camming levers and the perforated ears 54, 54.

The present invention contemplates a single elongated torsion spring device 62 for biasing the camming levers 44, 44 with respect to the release lever 48 and shaft 38. The spring construction 62 includes a pair of coiled spring portions 64, 64 connected by a length of wire 66. The spring device 62 is sleeved around the shaft 38 with its end portions 64, 64 adjacent the camming levers 44, 44 and with its connecting wire 66 inserted through the slot 42 of the shaft and extending along the interior of the shaft. The ends 68 of the spring device are offset from the outermost convolution and are hooked around the camming levers 44, 44 adjacent the outer ends thereof. The net result of this arrangement of the spring device is that the spring device is held in a relationship which is fixed with respect to the shaft and to the frame of the buckle as a result of the nonrotative mounting of the shaft 38. The camming levers 44, 44 are biased in such a direction that said levers engage the edge 70 of the release lever 48 and urge the lever toward closed position.

Referring to FIG. 4, the release of the buckle involves the movement of the lever 48 in a clockwise direction to the point that the camming levers 44, 44 are driven in a similar direction a sufficient distance to permit the coupling member 14 to rise over the bulging portions 32, 32 and thereby be free to be withdrawn. The reengagement of the coupling members takes place as shown in FIG. 2. As the coupling member 14 is pushed to the left, the camming levers 44, 44 are rotated by the force applied by the end of the coupling member 14. The movement of the camming levers a sufficient distance to permit the inser-

tion of the buckle component 14 takes place without any corresponding movement of the release lever 48, and the engagement is opposed only by the spring 62.

A knurled pin 76 is slidably mounted in a cutout portion 78 formed in the base 28 and is adapted to receive the end of the belt 20 therearound. When the release lever 48 is in uppermost moved position the belt may be moved with respect to the pin for adjusting the effective length of the belt. When the lever 48 is returned to normal position, the lever clamps the belt between the pin and the edge of the cutout portion.

While I have illustrated and described the preferred embodiment of my invention, it is to be understood that I do not limit myself to the precise construction herein disclosed and that various changes and modifications may be made within the scope of the invention as defined in the appended claims.

Having thus described my invention, what I claim as new, and desire to secure by United States Letters Patent is:

1. A safety belt buckle comprising a first coupling member, said first coupling member being in the form of a flat plate and having belt-engaging means and a pair of spaced slots; and a second coupling member, said second coupling member including a frame having a substantially flat base portion and bulging portions projecting from said base portion and adapted to engage said slots, said frame also including opposite parallel flanges disposed on the same side of said base portion as said bulging portions, a cylindrical shaft extending between said flanges and non-rotatively mounted therein, said shaft having an elongated slot therein, camming levers rotatably mounted on the ends of said shaft between said flanges, a release lever rotatably mounted on said shaft and having a driving edge disposed to engage and induce rotation of said camming levers on manual rotation of said release lever from a position adjacent said base portion toward a position perpendicular thereto, and common means for biasing said release lever toward a position against said base portion and for urging said camming levers against the driving edge of said release lever, said camming levers being positioned to maintain the engagement of said first coupling member with said bulging portions with said release lever adjacent said base portion and provide clearance for the escape of said first coupling member from said bulging portions on manual rotation of said release lever to a position approaching perpendicularity to said base portion, said second coupling member also having a belt-receiving portion, said common biasing means comprising an elongated spring device having coiled end formations around the ends of the shaft with the extremities of the forma-

tions hooked around the camming levers, the midportion of the spring device being secured in the slot in the shaft.

2. A safety belt buckle comprising a first coupling member, said first coupling member being in the form of a flat plate and having belt-engaging means and a pair of spaced slots; and a second coupling member, said second coupling member including a frame having a substantially flat base portion and bulging portions projecting from said base portion and adapted to engage said slots, said frame also including opposite parallel flanges disposed on the same side of said base portion as said bulging portions, a cylindrical shaft extending between said flanges and non-rotatively mounted therein, said shaft having an elongated slot therein, camming levers rotatably mounted on the ends of said shaft between said flanges, a release lever rotatably mounted on said shaft and having a driving edge disposed to engage and induce rotation of said camming levers on manual rotation of said release lever from a position adjacent said base portion toward a position perpendicular thereto, and common means for biasing said release lever toward a position against said base portion and for urging said camming levers against the driving edge of said release lever, said camming levers being positioned to maintain the engagement of said first coupling member with said bulging portions with said release lever adjacent said base portion and provide clearance for the escape of said first coupling member from said bulging portions on manual rotation of said release lever to a position approaching perpendicularity to said base portion, said second coupling member also having a belt-receiving portion, said common biasing means comprising an elongated spring device having coiled end formations around the ends of the shaft with the extremities of the formations hooked around the camming levers, the other transverse edge of the release lever being bent outwardly forming a handle for manipulation of the release lever, and washers interposed between the sides of the release lever and the camming levers, the midportion of the spring device being secured in the slot in the shaft.
